US0D1074483S

(12) **United States Design Patent** (10) **Patent No.:** **US D1,074,483 S**
(45) **Date of Patent:** ** *May 13, 2025

(54) **VISUAL INDICATOR**

(71) Applicant: **Reign RMC, LLC**, Summerland Key, FL (US)

(72) Inventors: **Richard Vanek**, Summerland Key, FL (US); **Rodney Montrose**, Pensacola, FL (US); **Donald Connor**, El Dorado, AR (US)

(*) Notice: This patent is subject to a terminal disclaimer.

(**) Term: **15 Years**

(21) Appl. No.: **29/886,680**

(22) Filed: **Mar. 11, 2023**

(57) **CLAIM**

The ornamental design for a visual indicator as shown and described.

DESCRIPTION

FIG. 1 is a perspective view of a visual indicator showing our new design.

FIG. 2 is an exploded view thereof;

FIG. 3 is a front view thereof;

FIG. 4 is a rear view thereof;

FIG. 5 is a side view thereof; and,

FIG. 6 is a front view thereof installed on above-ground fluid storage tank.

The broken lines used for an above-ground fluid storage tank in FIG. 6 is included for the purpose of illustrating environmental structure while all other broken lines illustrate portions of the visual indicator; the broken lines form no part of the claimed design.

1 Claim, 6 Drawing Sheets
